(57) **CLAIM**

An ornamental design for a vehicle headlight, shown and described.

DESCRIPTION

FIG. 1 is a front elevational view of a left vehicle headlight (both the left and right vehicle headlight being mirror images and only one is shown);

FIG. 2 is a left side elevational view of the vehicle headlight; FIG. 3 is a right side elevational view of the vehicle headlight; FIG. 4 is a top plan view of the vehicle headlight; and, FIG. 5 is a bottom plan view of the vehicle headlight.

Shading is used to illustrate the curvature of the part and not color. Any functional features of the vehicle headlight are not claimed. Views are orthogonal projections rendered from computer aided design data. The various views are not necessarily to scale in order to better illustrate the design.
